UNITED STATES PATENT OFFICE.

NETTIE BARRETT, OF MOUNT STERLING, OHIO.

CANNING DEVICE.

972,800.

Specification of Letters Patent. Patented Oct. 18, 1910.

Application filed October 19, 1909. Serial No. 523,488.

To all whom it may concern:

Be it known that I, NETTIE BARRETT, a citizen of the United States, residing at Mount Sterling, in the county of Madison 5 and State of Ohio, have invented certain new and useful Improvements in Canning Devices, of which the following is a specification, reference being had to the accompanying drawings.

This invention has relation to certain new and useful improvements in devices of that character which are adapted to support a plurality of cans containing fruits, vegetables, and the like to be cooked by steam, 15 the device being positioned within a boiler or other suitable receptacle which is partially filled with water, the steam rising therefrom cooking the contents of the cans.

A further object is to provide a can-holding frame which is collapsible and when not in use may be readily folded and stored away.

Another object of the invention is to provide a novel form of frame base which is formed from a single length of wire, the space inclosed thereby being divided by a plurality of intersecting wires and adapted to receive bottles in the spaces thus divided to support the bottles while filling the same 30 with grape juice, cider or other material to be preserved.

A still further object is to provide a knock-down frame having bail members at its ends, said members having loops formed 35 in their vertical portions to receive the downwardly extending corners of a removable can-supporting frame, the base of said frame having a downwardly extending loop at each of its corners to support the same, 40 said bails being pivoted to the ends of the base frame.

With these and other objects in view, the invention consists of the novel construction, combination and arrangement of parts hereinafter fully described and claimed and illustrated in the accompanying drawings, in which—

Figure 1 is a vertical section through a boiler showing the support positioned thereon; Fig. 2 is a perspective view of the device removed; Fig. 3 is a detail fragmentary view of one corner of the can-supporting frame and a portion of one of the bail members, showing the same detached; Fig. 4 is a 55 similar view, showing the corner of the

frame engaged in the loop of the bail member; Fig. 5 is a detail perspective view of one corner of the base frame illustrating the manner in which the wire is bent to provide the supporting feet; and Fig. 6 is a detail 60 perspective view of a slightly modified form of the removable can supporting frame.

Referring to the drawings 5 indicates a boiler which may be of any suitable construction and is provided with a removable 65 cover 6. Within the boiler my improved can-supporting frame is adapted to be positioned. This frame comprises a base member 7 which is formed from a single length of wire bent into substantially rectangular 70 form. At each of the corners of the base member the wire is bent downwardly and looped as shown at 8 to provide suitable supports which are adapted to dispose the base frame above the bottom of the boiler 75 when the device is in position as clearly shown in Fig. 1. The space inclosed by the boundary wire of this frame is divided by a plurality of intersecting wires 9 to provide a convenient number of smaller spaces 80 which are adapted to receive and support bottles or preserving jars so that the same may be conveniently filled with fruit juices or the like which it is desired to preserve.

To the ends of the base frame and adjacent to each of its sides, the ends of the bail wires 10 are pivotally connected by coiling the same thereon. The central portion of these wires is bent to provide the bail or handle portions 11. The parallel 90 vertical portions of the wires 10 are bent upon themselves or looped as clearly shown at 12 in Figs. 3 and 4. These loops are adapted to receive the corners of a rectangular can-receiving frame 13. In order to 95 provide suitable means for connecting the corners of the frame to the bail wires, the boundary wire of the frame 13 is downwardly bent at its corners and formed with a loop 14. The end portion of this loop is 100 compressed or brought together to form a somewhat contracted portion 15. The oppositely bowed wires which comprise the loops 14 are capable of compression thus providing a resilient member which when 105 the same is inserted in the loop 12 of the bail wires will prevent the accidental disengagement of the frame 13 therefrom. It will be noted from reference to Fig. 1 that the loops 14 are somewhat curved longi- 110

tudinally and have their ends 15 engaged with the bail wires. When it is desired to move the frame 13 considerable force must be exerted to compress the loops 14 so that 5 the same may be drawn through the bail loops 12. The space inclosed by the wire of the frame 13 is likewise divided into a plurality of smaller spaces by the cross wires 16 in a similar manner to the lower base 10 frame 7, the only difference being that a smaller number of divisions is provided. When the device is in position within the boiler, the cans are placed in the frame, and are supported upon the base member 7, the 15 upper ends of the cans extending slightly above the upper frame member 13. The boiler is partially filled with water and the steam which rises therefrom will perform the greater portion of the cooking operation. 20 In Fig. 6 there is illustrated another form of the can supporting frame, which differs from that shown in Fig. 2 only in the provision of a greater number of divisions which are provided by the intersecting 25 wires 16'. Otherwise the construction of this form of the frame is similar to that previously described.

From the foregoing it will be seen that I have provided a device which is particularly adapted for use in canning and preserving fruits or vegetables. Heretofore it has been customary to place the cans within the boiler, but to insure the cans retaining their upright position therein, the boiler had 30 to be entirely filled whether there was sufficient material to fill all of the cans or not. By means of the device above set forth, a smaller number of cans may be positioned in the boiler and more satisfactory results 35 will be obtained as greater space is provided for the circulation of the steam about the cans. When it is no longer desired to use the support, the upper can-receiving frame 13 is removed and the bail members 10 40 folded inwardly and downwardly upon the base frame 7. The entire device may then be compactly arranged and laid away for future use. The holder is completely constructed of wire which would preferably be 45 formed of steel or galvanized iron suitably treated to render the same non-corrodible. It will be obvious that owing to the extremely simple construction of the frames and bail members, the device may be manufactured and retailed at an extremely low 50 figure. It is, however, strong, rigid, and durable in its construction.

It will be understood that numerous minor modifications may be resorted to in 60 regard to the form, proportions and details of construction without departing from the essential features or sacrificing any of the advantages of the invention.

Having thus described the invention, what 65 is claimed is:

1. In a device of the character described, the combination of a base frame, said frame comprising a boundary wire formed of a single length of material, said wire being bent into substantially rectangular form 70 and provided with downwardly bent loops at its corners to form supporting feet, crossed wires secured between the boundary wires and adapted to divide the space inclosed thereby into a plurality of spaces of 75 equal size, a bail member pivotally secured to each end of said frame adjacent to the loops, said bail members comprising the vertical parallel portions and the curved connecting bail portions, the vertical portions 80 being bent to provide laterally extending loops, said loops extending inwardly, and a can-supporting frame formed from a single length of wire, said wire being downwardly extended at the corners of the frame and 85 adapted to be removably positioned in the loops of said bail members, the space inclosed by said frame wire being divided into a plurality of smaller spaces by intersecting wires secured to said frame wire. 90

2. In a device of the character described, the combination of a base frame having supporting feet at its corners, said frame comprising a boundary wire, the sides and ends of said frame wire being connected by a plurality of intersecting wires, a bail secured to the opposite ends of said frame, said bails each being formed from a single length of wire bent between its ends to provide inwardly extending loops, a can-supporting frame disposed above the base frame and parallel therewith, said frame consisting of a single length of wire bent into substantially rectangular form, said wire being downwardly and outwardly extended at the 100 corners of said frame and bowed in opposite directions to provide a resilient loop, the ends of said bowed portions being brought together to form a contracted termination, said bowed portions being insertable through 105 the loops of the bail members and adapted to be sprung inwardly to secure the frame in said loops, and a plurality of crossed wires secured between said frame wire adapted to receive and support a plurality of cans on 110 said base frame. 115

3. In a device of the character described, the combination of a rectangular base frame having a supporting leg at each corner thereof, said frame being adapted to receive 120 and support a plurality of bottles, a bail member pivotally secured to each end of said frame, a can receiving frame formed from a single length of wire bent between its ends to provide resilient loop portions, each 125 of said bail members being formed from a single length of wire bent to provide inwardly extending loops, the loops of said bails being adapted to receive the corner loops of said frame to removably support 130

the same, and a plurality of crossed wires secured to said frame wire and dividing the space inclosed thereby into a plurality of can-receiving spaces, said bail members being adapted to be folded inwardly and downwardly upon the base frame, when said can supporting frame is removed therefrom.

In testimony whereof I hereunto affix my signature in the presence of two witnesses.

NETTIE BARRETT.
